Primary Examiner — Omeed Agilee*(74) Attorney, Agent, or Firm* — Greenberg Traurig, LLP(57) **CLAIM**

The ornamental design for an electrode device as shown and described.

DESCRIPTION

FIG. 1 is a perspective view of an electrode device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dot-dash-dot broken lines in the drawings depict boundaries of the claim and form no part of the claimed design. The short dashed lines in the drawings depict environmental subject matter and form no part of the claimed design.
